UNITED STATES PATENT OFFICE.

ELMER H. SMITH, OF MINNEAPOLIS, MINNESOTA.

PREHEATING TORCH AND METHOD OF OPERATING THE SAME.

Application filed December 26, 1923. Serial No. 682,768.

To all whom it may concern:

Be it known that I, ELMER H. SMITH, a citizen of the United States, resident of Minneapolis, county of Hennepin, and 5 State of Minnesota, have invented certain new and useful Improvements in Preheating Torches and Methods of Operating the Same, of which the following is a specification.

10 My invention relates to preheating torches in which a suitable liquid fuel such as kerosene is converted into a combustible vapor for the heating flame. Torches of this kind are frequently used in places 15 where the temperature is comparatively high and sometimes in places where the temperature is very low. Evidently in a high atmospheric temperature the walls and vaporizing coil will become heated to 20 such a degree of intensity that the flame of the burner will be shortened on account of the delivery of a smaller volume of fuel and the efficiency of the torch will thereby be reduced. When the torch is used in a 25 very cold place, the coil and the walls of the torch will be so affected that proper vaporization will be retarded.

The object therefore of my invention is to provide a torch having means for reducing 30 the temperature of the coil and walls of the torch or to correspondingly raise the temperature when it is desirable to do so in the operation of the device.

The invention consists generally in various constructions and combinations all 35 as hereinafter described and particularly pointed out in the claims.

In the accompanying drawings forming part of this specification.

40 Figure 1 is a longitudinal sectional view through a preheating torch embodying my invention showing it adapted for reducing the temperature of the vaporizing coil;

45 Figure 2 is a similar view showing how the torch may be adapted for raising the temperature of the coil;

Figure 3 is a sectional view on the line 3-3 of Figure 2.

50 In the drawing, 2 represents a casing of suitable material, preferably cylindrical in form, having a head 3 fitting within one end with an opening therein substantially concentric with the bore of the casing and provided with an annular flange 4, preferably having converging walls, and a discharge opening 5 through which the flame

is projected upon the surface to be heated.

At the other end of the casing is a head 6 fitting within the open end of the casing and provided with a duct 7 which communicates at its outer end with a passage 8 arranged in a block 9 which closes the end of a pipe 10 that is tapped or otherwise mounted on the outer end of the head 6. A rod 11 has a needle valve 12 at one end which has threaded connection with the walls of the passage 8 in the block 9 and provided with a series of longitudinal ducts 13 through which the liquid fuel may flow from the pipe 10 to the duct 8. When 70 this rod 11 is moved in to the limit of its stroke the needle valve will close the passage 8 and shut off the flow of liquid fuel to the duct 7. A pipe 14 connects the duct 7 with a passage 15 in the head 3 and said passage extends around within said head to the opposite side thereof and is connected to one end of a vaporizer preferably a coil 16 that is arranged within the casing 2. The other end 17 of said coil communicates with a passage 18 in the head 6 which leads to the burner nozzle 19 and through which the vaporized fuel is delivered to said nozzle. A ring 20 is fitted within the open end of the casing 2 and is provided with a 85 series of ports 21 and a central opening 22 that is opposite the discharge end of the nozzle 19. A damper ring 23 is mounted to rotate on the ring 20 and is provided with openings adapted to register with the openings 21; a finger grip 24 being provided for convenience of the user in rotating the ring 23 and exposing the openings 21 or closing them. The rings 20 and 23 form in effect 90 a damper by means of which air may be admitted to the casing or shut off, as may be desired, in the operation of the torch.

Opposite the opening 22 and within the vaporizing coil I provide a tube 25, preferably tapered, having its smaller end opposite and adjacent the opening 22 and its larger end near the outlet or outer end of the coil; a space being provided between the smaller end of the tube and the adjacent ring 20. When the damper is closed entirely, air for combustion will flow through the opening 22 and mingle with the vapor from the burner, the flame being projected through the tube 25 and a considerable distance beyond the outer end of 110 the torch. If the coil and the walls of the casing become heated to a high degree so

that the temperature of the vapor and its expansion are increased beyond the desired point, the operator will open the damper and thereupon a volume of cold air will flow 5 into the space between the casing and the tube 25 and circulate around and cool the walls of the vaporizing coil. This is due to the fact that the flow of the vapor produces a vacuum around the outer or larger 10 end of the tube 25 so that when the damper is opened, air will be sucked in through the openings therein and made to flow around the coil to reduce its temperature. Generally the opening 22 is insufficient to supply 15 the tube with air and a supply of air is delivered through the damper openings.

I have found in actual practice that a casing and coil heated to a red heat can be cooled to the desired temperature in a 20 few moments. If the damper is closed, a vacuum will be formed at the smaller end of the tube which is stronger than the vacuum at the large end and a suction will be established backwardly between the coil and the 25 casing and around the convolutions of the coil and heated air and the flame and products of combustion will be drawn in between the coil and the casing and serve to raise the temperature of the coil and the 30 vapor therein, as indicated by the arrow in Figure 2. This is due to the fact that the damper being closed and the air rushing in through the opening 22 and mingling with the gas will form a stronger vacuum 35 at the smaller end of the tube and set up a backward circulation around the convolutions of the coil. I am thus able, by the manipulation of the damper, to control currents of air at either end of the tube and 40 set up a circulation of cool air in one direction around the coil or currents of heated air and flame in the other direction around the coil, depending upon whether the operator wishes to lower the temperature of 45 the coil and vapor or raise it. I have found in actual practice that I can accurately regulate the flow of cold and heated air around the coil and thus govern the temperature of the vaporizer and vapor according to atmospheric conditions and the place where 50 the torch may be in use.

I claim as my invention:

1. A torch comprising a fluid fuel burner, a vaporizer, a flue within said vaporizer through which the flame of said burner is directed, a casing and means cooperative with said casing and vaporizer for causing the products of combustion to flow from the outlet of said flue backwardly around the vaporizer to heat the walls thereof.

2. A torch comprising a liquid fuel burner, a vaporizer coil, a flue within said coil through which the flame from said burner is directed, and means for causing 65 the products of combustion to flow from the

outlet of said flue backwardly around the convolutions of said coil to heat the walls thereof, said means comprising a wall opposite said burner and provided with a flame opening spaced from said flue intake 70 and damper controlled air intake openings grouped around said flame opening.

3. A torch comprising a liquid fuel burner, a casing having intake and outlet openings, a vaporizer within said casing, a flue within said vaporizer through which the flame from said burner is directed to said outlet opening, said casing and vaporizer having an air circulating passage between them communicating with the outlet 80 openings of said flue and casing, and means adjacent said burner for admitting air to said circulating passage to flow outwardly to the outlet opening of said casing through said passage and around said vaporizer to 85 cool it.

4. A torch comprising a liquid fuel burner, a casing having intake and outlet openings, a vaporizer within said casing, a circulating passage being provided between 90 said vaporizer and the wall of said casing, a flue within said vaporizer through which the flame is directed from said burner, said flue being spaced from said inlet opening and communicating at each end with said 95 circulating passage, means for excluding air from said passage, and causing a suction between said inlet opening and flue when the air intake of said passage is closed and setting up a backward draft in said 100 passage to draw the flames and products of combustion backwardly around the said vaporizer to heat it.

5. A torch comprising a liquid fuel burner, a casing having an outlet opening 105 and a wall in one end provided with a flame opening and air-intake openings provided in said wall around said flame opening, a damper for said air intake openings, a vaporizing coil within said casing, 110 a flue within said coil through which the flames from said burner pass to said outlet opening, a circulating passage being provided between said coil and flue and the wall of said casing communicating with each 115 end of said flue, and with the outlet opening of said casing, said damper when open creating a suction at the outer end of said flue and drawing the cold air into said circulating passage around the convolutions of 120 said coil to cool them, and said damper when closed creating a suction between said flue and inlet opening and drawing the flame and products of combustion backwardly through said circulating passage 125 around the convolutions of said coil to heat them.

6. A device of the class described comprising a burner head having a duct therefor in communication with a source of lia- 130

uid fuel supply, a casing having a head at its outer end provided with an outlet opening, and a duct encircling said opening and having a pipe connection with the 5 duct in said burner head, a burner tip mounted in said head, a vaporizer coil communicating with the duct of said casing head and with said burner tip, a flue within said coil, a wall arranged in said casing 10 and having an inlet opening opposite said burner tip, a circulating passage being formed between said flue and the wall of said casing, and communicating with the outlet of said casing, and a damper device 15 encircling said inlet opening in said wall and controlling the admission of air to said circulating passage.

7. A torch comprising a liquid fuel burner, a casing having intake and discharge openings, a vaporizer within said casing, a circulating passage being provided between said vaporizer and casing communicating with said inlet and discharge openings, a flue within said vaporizer extending partially therethrough and having its 20 outlet opening remote from the outlet opening of said casing, said burner having means 25

for receiving air for combustion between it and the inlet opening of said casing and said casing having means for admitting or 30 shutting off the flow of cold air to said circulating passage.

8. A method of heating a torch vaporizer which consists in projecting the burner flame through the vaporizer and causing 35 regulated amounts of the products of combustion to flow backwardly into contact with the walls of the vaporizer to regulate the temperature thereof.

9. A method of regulating the temperature of the walls of a torch vaporizer which consists in projecting a burner flame through the vaporizer, admitting air to circulate around the vaporizer between it and the torch casing to cool the walls of the vaporizer and causing regulated amounts of the products of combustion to flow backwardly between said vaporizer and the torch casing to regulate the heat of the walls of 45 said vaporizer.

In witness whereof, I have hereunto set my hand this 21st day of December, 1923.

ELMER H. SMITH.
